UNITED STATES PATENT OFFICE.

DE WITT C. HARRIS, OF FOND DU LAC, WISCONSIN, ASSIGNEE, BY MESNE ASSIGNMENTS, TO HARRIS TYPEWRITER MANUFACTURING COMPANY, OF FOND DU LAC, WISCONSIN, A CORPORATION OF WISCONSIN.

TYPE-WRITER.

1,115,070.

Specification of Letters Patent. Patented Oct. 27, 1914.

Original application filed April 15, 1912, Serial No. 690,756. Divided and this application filed May 2, 1914, Serial No. 764,969.

To all whom it may concern:

Be it known that I, DE WITT C. HARRIS, a citizen of the United States, residing at Fond du Lac, in the county of Fond du Lac and State of Wisconsin, have invented certain new and useful Improvements in Type-writers, of which the following is a specification.

his invention relates to typewriting machines and more particularly to the type actions thereof.

The objects of the invention are to provide such a relation of parts in the action that the type bars may be swung by a minimum amount of force; to provide for the transmission of the unequal arcs of movement of the three series of key levers into uniform arcs of movement of the type bars; to provide an action adapted for use with an improved form of key levers; and to otherwise improve and increase the efficiency of type actions as will be more fully pointed out hereinafter.

This application is a division of my prior application, Serial No. 690,756, filed April 15, 1912.

In the accompanying drawings, Figure 1 is a vertical sectional view through a typewriting machine equipped with a type action embodying the features of my invention. Figs. 2, 3 and 4 are views in a series illustrating the relation of the parts of individual actions for key levers of three different lengths.

In the embodiment of my invention which I have herein shown by way of example, the key levers and associated parts are mounted upon a frame, which frame and the parts mounted thereon constitute a unit which is assembled and then inserted bodily into the framework of the typewriter.

In the drawings, 5 indicates the side rails of the main framework of the typewriter and 6 are lugs projecting inwardly from said side rails. The unit frame in which the key levers and associated parts are mounted comprises a bar 7, a pair of end plates 8, forward and rear guide combs 9 and 10 for the key levers, and a guide comb 11 for the bell-crank comprised in the ac-

tion, said parts being secured together in any suitable way. The comb 11 comprises a base secured to the bar 7 and a forward portion which is curved upwardly and rearwardly to guide the series of bell-crank in 5 their pivotal movement. The bar 7 is secured to the lugs 6 by suitable fastenings.

The key levers 14 are pivoted upon a shaft 15 having its ends fixed in openings in the end plates 8 of the frame. Each of said key levers has its rear portion bent back upon itself to form an arm 16 lying edgewise alongside and above the body of the lever, said arm being pivoted on the key lever shaft 15 and the body of the lever running 65 beneath said shaft. This arrangement provides a resiliency in the lever which is very desirable. For a full understanding of the function and advantages of this form of key levers reference may be had to my co-pending application Serial No. 755,583, filed March 20, 1913, where the construction is fully described and claimed. The forward ends of the key levers carrying the keys 17 are normally maintained in their 70 uppermost position by coiled springs 18 attached at their upper ends to the key levers rearwardly of the shaft 15 and at their lower ends to a suitable fixed part, in the present instance the comb 11.

The type bar support comprises an arcuate portion or segment 20 and sides 21, said support in the machine illustrated being mounted for vertical sliding movement in suitable guideways in the frame. I have 75 deemed it unnecessary to herein illustrate the guiding means for the type bar support or the means for moving said support up and down, since the present invention does not relate thereto.

The platen is indicated at 22. The type bars 23 are arranged in arcuate series, and are pivoted in slots 24 in the segment 20. The free ends of the type bars are arranged to rest upon a suitable support or cushion 25, herein shown as being mounted on arms 26 which are fixed in the type bar support. The bases of the type bars have lugs or short arms 27 to which are attached the devices for imparting movement to the type 100

bars. In Fig. 2 the type bar is shown in its striking position, the normal position of the bar being indicated in dotted lines in Fig. 3.

The mechanism for connecting the key levers 14 to the type bars will now be described. Pivoted mounted on a shaft 30, which has its ends fixed in openings in the end plates 8 of the unit frame, is a plurality of bell-cranks 31, one for each of the key levers 14. The shorter arms 32 of said bell-cranks are connected by thrust links 33 with the forward ends of the arms 16 on the key levers, while the longer vertical arms 34 of the bell-cranks are connected 15 through horizontal links 35 with the short arms 27 on the bases of the type bars 23. In order to obtain the most efficient arrangement of this mechanism, the elements of each individual key lever action are constructed and connected in such relation that each of the pivoted elements is swung by a force exerted approximately at right angles to the radius of the element. It will be seen that the link 35 extends approximately 25 at right-angles to the arm 27 on the type bar and to the long arm 34 of the bell-crank. Also the link 33 acts at right angles to the short bell-crank arm 32 and the arm 16 on the key lever. Thus the force required to 30 depress one of the keys 14 is reduced to a minimum. The type bar segment is arc-shape, and the bases of the type bars are mounted on said segment at gradually increasing heights from the middle of the 35 series to the outer ends thereof. To maintain a horizontal pull of the links 35 substantially at right angles to the arms 27 on the type bars, the vertical arms of the bell-crank levers are gradually increased in 40 length from the middle of the series outward, so that their upper ends will describe an arc corresponding to the position of the bases of the type bars. Since the arc of swinging movement of the type bars 23 is 45 uniform throughout the entire series, the length of reciprocation of the upper ends of the longer bell-crank arms 34 must be the same for all of said arms in spite of the fact that they differ in length from the middle of the series outward. Thus while the 50 shortest of these vertical bell-crank arms 34 swings through the same rectilinear distance as the longest arms, the angle through which said shortest arm swings will be 55 greater than the angle of movement of the longest arm, and this angle will gradually decrease from the shortest arm in the center of the series of the longest arms at the outer ends thereof. Now in any one bank of the 60 key levers 14 the arc of movement of all of the levers is identical because the keys must all have a uniform distance of travel, and in order to communicate this uniform arc of movement of the key levers to the bell

cranks 31 in such a way that the upper ends 65 of the longer arms will move through the same rectilinear distance, the proportions and relations of the elements of each key action are varied corresponding to the varying lengths of the longer arms 34 of the 70 bell-cranks. This is accomplished in the present instance by varying the length of the portion of the key lever arm 16 forwardly of its shaft 15, varying the length of the short arms 32 of the bell-cranks and 75 also of the links 33, and varying the angles between the short arms and the long arms of the bell-cranks to suit the peculiar movement of each key lever action.

Referring to Fig. 2 which shows a key 80 lever action comprising one of the shortest key levers and one of the shortest vertical arms 34 of the bell-crank levers; let us suppose that the vertical arm 34 of the bell-crank is lengthened to correspond to one of 85 the outer key lever actions. The upper end of this lengthened arm, while it would travel through the same rectilinear distance as above explained, would swing through a smaller angle with reference to a circle than 90 a short arm. As before stated, however, all of the key levers 14 in a single series swing through the same arc, and the forward portion of the key lever arms 16 would likewise, if they were all of equal length, swing 95 through arcs of the same length. Therefore, in order that the constant and uniform length of swinging movement of the key levers will be transmitted to the longer arms of the bell-cranks, so as to swing them 100 through different arcs and cause their outer ends to move through the same rectilinear distance, the shorter arm 32 of the bell-crank in the example above supposed would be lengthened, so that movement communicated to it from the key lever arm 16 through the link 33 would move it through a smaller arc, and therefore would move the longer arm of the bell-crank through a smaller arc, thus carrying its outer end through the desired distance of reciprocation.

Thus far one element of the problem has been solved, namely, to vary the length of a shorter arm 32 in proportion to the increasing length of the longer arm 34, so that 115 said arms will be moved through smaller arcs to maintain the rectilinear movement of the outer ends of the longer arms constant for transmission to the links 35 and type bars 23. As above explained, it is 120 desirable in order to obtain the most effective arrangement that the force exerted upon a pivoted part should work at right angles thereto. Therefore the forward portion of the key lever arm 16 and the 125 shorter arm 32 of the bell-crank are maintained in substantially parallel relation in order that the link 33, if at right angles to

one, will be at right angles to both. Thus a line joining the center of the key lever shaft 15 and the pivotal center of the upper end of the link 33 will be approximately parallel to a line joining the center of the bell-crank shaft 30 and the pivotal center of the lower end of the link 33. Now if the shorter bell-crank arm 32 is lengthened to correspond to the longer arm of the bell-crank, the lower end of the link is moved forwardly which would destroy its right-angular relation if other adjustments were not made. Therefore the forward end of the key lever arm 16 is lengthened to also move the upper end of the link forwardly. The relation in length of the forward ends of the key lever arm 16 and the short arms 32 of the bell-crank levers is definite, say for example, 3 to 2. Therefore in changing said lengths to correspond to the varying length of the long bell-crank arm 34 the key lever arm 16 would be lengthened three units to two units of increased length in the short arm of the bell-crank. In other words, the upper end of the link 33 would be advanced forwardly more rapidly than the lower end which would result in destroying the right-angular relation of the link to the arms 16 and 32. To overcome this difficulty the angles between the short and long arms of the bell cranks are varied, and the angle with reference to a horizontal line of the forward portion of the key lever arm 16 is also varied, the bell-crank angle being increased for longer arms and the key lever arm correspondingly approaching a more nearly horizontal position, it being understood that the vertical arms of the bell-cranks are maintained in a vertical position. From this it will be seen that, given a uniform arc of movement of one entire bank or series of key levers, a uniform arc of movement of the entire series of type bars, and a varying length of the longer arms 34 of the bell-cranks, movement is transmitted from the key levers to the bell-cranks in such a manner as to cause the upper ends of all of the vertical bell-crank arms to move through a uniform distance of reciprocation, at the same time maintaining in each case the right-angular relation of the parts as described so as to have the most effective movement thereof and also permitting the use of an advantageous form of resilient key lever.

What has been said with reference to the key lever action for the shortest length of key levers, as shown in Fig. 2 applies generally to the action of the medium length key lever illustrated in Fig. 3, and to the longest lever shown in Fig. 4. Owing to the fact, however, that the three series of levers swing through different angles of movement in order to maintain the travel of

the keys 17 uniform for the three series, the length of the forward ends of the arms 16 will necessarily be different in the three series of levers for any given length of the vertical arms 34 of the bell-cranks 31. For, given one length of said long bell-crank 70 arm, to move said arm through the same arc, the forward end of the arm 16 of one of the longest key levers will necessarily be longer than the forward end of the arm 16 of one of the shortest key levers since the former key lever swings through a shorter arc of movement than the latter key lever, which movement must be increased in the case of the former lever by lengthening the arm 16 in order to obtain the same swinging movement of the bell-crank lever. In each series of key levers, however, the same variations of parts to compensate for the differences in the vertical arms 34 of the bell cranks will occur.

85

My invention is not limited to the precise construction herein disclosed, but said construction may be modified in various ways without departing from the scope of the invention as defined in the appended claims.

I claim as my invention:

1. In a typewriter, in combination, a series of type bars pivoted to strike upwardly and rearwardly, a series of key levers, a series of vertically disposed bell-crank levers pivoted at their angles below the series of key levers, each of said bell-crank levers comprising an upwardly extending arm and a forwardly extending arm, a series of links connected to and extending rearwardly from the upper ends of said upwardly extending arms, the rear ends of said links being attached to said type bars near their pivot points, and a series of thrust links extending upwardly from the ends of said forwardly extending bell-crank arms and connecting the latter to the series of key levers.

2. In a typewriter, in combination, a framework, a series of type bars pivoted at their rear ends to strike upwardly and rearwardly, a horizontal series of swinging key levers, a series of vertically disposed bell-crank levers pivoted at their angles in the framework beneath and between the ends of said series of key levers and forwardly of the pivots for the type bars, each bell-crank comprising a forwardly extending arm connected to a key lever, and an arm extending upwardly past the key lever, and pull links extending rearwardly from the last mentioned arms to the type bars.

3. In a type writer, in combination, a series of pivoted type-bars mounted to strike upwardly and rearwardly, a series of bell-crank levers, the arms of which increase in length from the center of the series toward the sides thereof, links connecting the up-

- wardly extending arms of said bell-crank to the type-bars, a series of key-levers each comprising two relatively yieldable sections disposed edgewise one above the other, and 5 links extending substantially at right angles to and connecting the laterally extending arms of the bell-crank to one of said key-lever sections, the angles between the arms of the bell-crank and the angle of the mentioned key-lever sections being varied throughout the series to maintain the right angular relation of the last mentioned links to the bell-crank arms and the mentioned key-lever sections.
- 15 4. In a typewriter, the combination with a series of type bars pivoted to strike upwardly and rearwardly, and a horizontal series of pivoted key levers, of a series of vertically disposed bell-crank levers pivoted 20 at their angles beneath the series of key levers, each bell-crank comprising an upwardly extending arm and a laterally extending arm, a series of links connecting the first mentioned arms to said type bars and 25 a series of approximately vertical thrust links connecting the laterally extending arms to said key levers, each set composed of a key lever, a bell-crank lever, and a thrust link, being so arranged that a line connecting the bell-crank pivot with the point of connection with its thrust link is substantially parallel to a line connecting the key lever pivot with the point of connection of the key lever and the thrust link.
- 30 5. A key-lever action for typewriters comprising a pivoted type-bar, a key-lever consisting of two relatively yieldable sections disposed edgewise one above the other; a key mounted upon one of said lever sections, a bell-crank pivoted at its angle beneath the key-lever and having a laterally extending arm connected to the other key-lever section, said bell-crank also having an upwardly extending arm extending past the 35 key-lever, and a link extending rearwardly from the latter arm and connected to said type-bar.
6. A key lever action for typewriters comprising a pivoted type bar, a key lever having an integrally connected arm lying above the body of the lever and fulcrumed to support the lever, a bell-crank lever pivoted at its angle beneath said key lever, said bell crank comprising a forwardly extending 40 arm and an upwardly extending arm, a link lying at one side of the key lever and connected at its lower end to said forwardly extending arm, and at its upper end to the forward end of said key-lever-arm, the upwardly extending arm of the bell crank projecting past the key lever, and a link connecting the last mentioned arm to the type bar for swinging the latter.
- 45 7. In a typewriter, in combination, an arcuate series of type bars, a series of key 65 levers pivoted on a horizontal axis and having a uniform swinging movement, a series of bell-crank pivoted on a horizontal axis, the vertical arms of said bell-crank increasing in length from the middle of the series 70 to its outer ends to correspond to the arcuate position of said type bars, links connecting the upper ends of said vertical arms to said type bars, and links connecting said key levers to the shorter arms of said bell-crank, 75 the length of said shorter bell-crank arms, the angle between the shorter and longer bell-crank arms, and the angle of said key levers being varied throughout the series to correspond to the varying length of said 80 vertical bell-crank arms, whereby the second mentioned links will extend at right angles to said shorter bell-crank arms and said key levers, and the uniform swinging movement of said key levers will impart different angles of movement to said bell-crank to equalize the rectilinear travel of the upper 85 ends of said vertical arms.
8. In a typewriter, in combination, a framework, an arcuate series of upwardly 90 and rearwardly striking type bars pivoted in said framework, a horizontal series of key levers fulcrumed in the framework, a series of vertically disposed bell-crank levers mounted in the framework on coaxial horizontal pivots, each bell-crank comprising an approximately vertical arm and an approximately horizontal arm, the vertical arms 95 gradually increasing in length from the middle of the series to the outer ends thereof to correspond to the arcuate position of the type bars, substantially horizontal links connecting the upper ends of the vertical arms to said type bars, the horizontal arms of the bell-crank being varied in length to correspond to the vertical arms, and a series of 100 links, each of which has its opposite ends pivotally connected in right-angular relation to one of said horizontal arms and one of said key levers, the angles between the arms 105 of the different bell-crank being varied to maintain the right angular relation of the last mentioned series of links.
9. In a typewriter, in combination, a framework, an arcuate series of type bars 115 pivotally mounted in said framework to strike upwardly and rearwardly, a horizontal series of swinging key levers, a series of vertically disposed bell-crank levers pivoted at their angles in the framework beneath 120 and between the ends of said series of key levers and forwardly of the pivots for the type-bars, each bell-crank comprising a laterally extending arm connected to a key-lever and an arm extending upwardly past 125 the key levers, the latter arms gradually increasing in length from the middle of the series to the outer ends thereof to correspond

to the arcuate position of the type bars, the laterally extending arms of said bell-crank being varied in length to compensate for the variation of said upwardly extending arms, and substantially horizontal links connecting said upwardly extending arms to the type bars.

In testimony whereof I affix my signature in the presence of two witnesses.
